UNITED STATES PATENT OFFICE.

CHARLES EDWIN SEARCH, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

STEAM-TURBINE.

1,187,452.

Specification of Letters Patent. Patented June 13, 1916.

Application filed August 13, 1913, Serial No. 784,780. Renewed September 20, 1915. Serial No. 52,114.

To all whom it may concern:

Be it known that I, CHARLES EDWIN SEARCH, a citizen of the United States, residing at Milwaukee, in the county of Milwaukee and State of Wisconsin, have invented a certain new and useful Improvement 5 in Steam-Turbines, of which the following is a specification.

This invention relates to steam turbines and more particularly to the means for 10 securing the shroud strip to the blade and with especial reference to the finished condition of the shroud strip.

The object of the invention is to secure a shroud strip to the ends of a plurality of 15 turbine blades in a secure manner with facility of fastening same and yet preserving certain advantages of the completed structure as will be pointed out hereinafter.

Heretofore it has been usual to secure 20 the shroud strip to a plurality of turbine blades by riveting over integral tenons formed on the ends of the blades, punching corresponding holes in the shroud strip 25 through which the tenons are first passed and which they closely fit, before the riveting over is done. This was a convenient means of fastening and possessed certain advantages that it is unnecessary here to 30 point out. The defects of this mode of fastening were that the shroud strip was not so securely held as to prevent certain vibrations which the present invention absolutely prohibits. Another disadvantage was that 35

in some cases it happened that when some of the turbine blades were a few thousandths of an inch shorter than they should have been, there was no support of the shroud strip portion immediately adjacent 40 the end of the short blade, during the riveting of the tenon on that blade. The consequence was that either the shroud strip was distorted in order to bring that portion into contact with the end of the short blade, or 45 the tenon was riveted over at a point so that a space was left between the shroud strip portion and the shoulder of the short blade, or both of these defects were present at the same time.

Another objection to the riveting-over of 50 tenons integral with the blades was that the rivet heads served as a series of paddles during the rotation through the expansive fluid under pressure. It has even been alleged by certain experts that the liquid of

condensation was present during the rotation, immediately adjacent the shroud strip and if that is true, under certain extreme conditions the rivet heads would still more act as baffles with a consequent decided 60 brake action on the rotation.

It is understood that in the prior art it has been proposed to wire the ends of the blades in various ways to connect same for the purpose of stiffening and spacing. Also 65 strips having teeth bent over to conform to the section of the blades have been proposed to be located adjacent the ends of the blades, but in either case these devices reduce the effective length of the blades, and 70 also place an obstruction in the path of the elastic fluid.

In the case of the wire, the baffling effect to prevent the fluid from passing around the ends of the blades is also not possible 75 therewith, which, as is well known, must be prevented in the Parsons type of turbine. The blades in that case must run close to the spindle or cylinder. These wires and strips have in some instances been 80 proposed to be brazed or soldered into place to the end blades of a segment, but always adjacent the ends of the blades where it is objectionable as noted. It has also been proposed to weld thin supporting strips to 85 or near the ends of blades and then solder heavy stiffening rings to the strips, but these constructions are indicated as for producing unitary vane structures for ready application to or removal from a turbine. 90 These would therefore be for foundation strip purposes and would not produce a single thin strip for shroud baffling purposes.

In the present invention, an absolute fastening means is provided for a single shroud 95 strip, the shroud strip may for baffling purposes run close to the spindle or cylinder as the case may be, and thus prevent leakage, and a smooth construction of shroud strip is had preventing all paddle brake action to the rotation.

Referring to the drawing.—Figure 1 is a plan view of a segment of blades partly broken away. Fig. 2 is an elevation of same partly broken away and in section. Fig. 3 105 is a transverse section of the same. Figs. 4 and 5 are transverse sections of modifications.

Referring to the drawings, a plurality of blades 1 is shown in union with a founda- 110

tion strip 2, and this may be any well known means of fastening the roots of the blade to the strip for insertion later into the spindle or cylinder 3, for instance, by calking in the strip 2 into a groove in the spindle or cylinder.

At the outer end of the plurality of blades 1 is located a shroud strip 4 conveniently shown of channel section, and this strip is secured by means of soldering or brazing, to the extreme ends of the blades 1 against which it abuts. It may be welded in place, but this would objectionably distort the parts due to the extreme heat required.

In order to insure that the blades are correctly spaced and angled about their axes, the blades are shown in Figs. 3 and 4 as having integral tenons formed thereon by cutting away the two sides of each blade end, leaving the tenon preferably with two parallel sides and with two curved sides, the latter lying in the blade surfaces. The shroud strip is correspondingly punched with holes of the same cross section as that of the tenons and these latter extend into and fill these holes in the shroud strip, leaving the ends of the tenons in Fig. 3 flush with the surface of the shroud strip between the channel sides. In Fig. 4 the tenon is headed over as usual. In Fig. 5 the tenon is omitted and the spacing and angling of blades are secured by other means. Both the devices of Figs. 4 and 5 are less preferable, that of Fig. 4 because of the paddle action of the tenon heads, and that of Fig. 5 because of the necessity of some external means of spacing and angling of the blades. The modification of Fig. 4 may be considered an improvement of the existing prior art of riveting over of tenons and may be further improved by removing the tenon heads altogether.

The ends of the blades 1, as thus coacting with the shroud strip 4, are then soldered to the strip, preferably by having the segment of blades inverted so as to bring the shroud strip 4 at the bottom. This will more conveniently serve to insure that the liquid solder flow between the ends of the blades and the strip. It will as a matter of fact, build up slightly along the margin of the blade end where it touches the strip 4 so as to form a fillet 5, as indicated in Figs. 2 and 3. For small blades which are close together, such as those at the high pressure end of the turbine, it has been found more convenient to perform the soldering operation having the segment of blades in such a position as to bring the shroud strip 4 at the top. In such case the solder will flow through the interstice between the tenon and the hole in the shroud strip. It is entirely unnecessary to have any connection between the tenon and the shroud strip, as it has been found by actual test that the soldered

connection between the end of the blade and the shroud strip is stronger than any tension stress to which the blade may be subjected, even to an actual fracture by tension of the blade itself. It has been found also by test, that this soldered connection between the blade end and the shroud is more than twice as strong as the riveted-over tenon connection of the prior art. 70

It should be noted that after soldering, the shroud strip presents a smooth surface of revolution throughout and that consequently there is no paddle brake effect on the rotation. 75

The early prior art construction where a shroud strip is made in the form of a ring shrunk or screwed on, has not been heretofore considered because that has been superseded by the riveted-over tenon type heretofore discussed. Such a strip is notoriously objectionable because the screws become loose, are too large for commercial application to small blades, or the strip itself becomes detached, and generally and especially the strip cannot be prevented from becoming loose on account of the vibration to which the parts are subjected in use. 80 85 90

It should be understood that it is not desired to be limited to the exact details of construction shown and described, for obvious modifications will occur to a person skilled in the art. 95

It is claimed and desired to secure by Letters Patent,

1. The combination of a plurality of blades and a single thin shroud strip abutting the ends of said blades at least at end surfaces adjacent both edges of said blades and soldered thereto. 100

2. The combination of a plurality of blades and a single thin shroud strip coacting with the extreme ends of said blades at least at end surfaces adjacent both edges of said blades and soldered thereto. 105

3. The combination of a plurality of blades and a single thin shroud strip having means for spacing said blades and for determining their proper angle, said strip being soldered to the extreme ends of said blades, at least at end surfaces adjacent both edges of said blades. 110 115

4. The combination of a plurality of blades and a single thin shroud strip having means for spacing said blades, said strip being soldered to the extreme ends of said blades, at least at end surfaces adjacent both edges of said blades. 120

5. The combination of a plurality of blades and a single thin shroud strip having spacing and angle-determining means for said blades, said strip being soldered to the ends of said blades and presenting a smooth surface of revolution throughout. 125

6. The combination of a plurality of blades and a single thin shroud strip hav- 130

ing spacing means for said blades, said strip being soldered to the ends of said blades and presenting a smooth surface of revolution throughout.

7. The combination of a plurality of blades and a single thin shroud strip having spacing and angle-determining means for said blades, said strip being soldered to the ends of said blades at least at end surfaces adjacent both edges of said blades and presenting a smooth surface of revolution throughout.

8. The combination of a plurality of blades and a single thin shroud strip having spacing means for said blades, said strip being soldered to the ends of said blades at least at end surfaces adjacent both edges of said blades and presenting a smooth surface of revolution throughout.

9. The combination of a plurality of blades and a single thin shroud strip abutting the ends of said blades and soldered thereto, no portion of the original shape of said blades projecting beyond the outer surface of said shroud strip.

10. The combination of a plurality of blades and a single thin shroud strip coacting with the extreme ends of said blades and soldered thereto, no portion of the original shape of said blades projecting beyond the outer surface of said shroud strip.

11. The combination of a plurality of blades and a single thin shroud strip having means for spacing said blades and for determining their proper angle, said strip being soldered to the extreme ends of said blades, no portion of the original shape of said blades projecting beyond the outer surface of said shroud strip. 35

12. The combination of a plurality of blades and a single thin shroud strip having means for spacing said blades, said strip being soldered to the extreme ends of said blades, no portion of the original shape of said blades projecting beyond the outer surface of said shroud strip. 40

13. The combination of a plurality of blades and a single thin imperforate shroud strip abutting the ends of said blades and soldered thereto. 45

14. The combination of a plurality of blades and a single thin imperforate shroud strip coacting with the extreme ends of said blades and soldered thereto.

In testimony whereof, the signature of 55
the inventor is affixed hereto in the presence
of two witnesses.
